Specification for Design.

Patented Feb. 13, 1917.

Application filed November 14, 1916. Serial No. 131,350. Term of patent 7 years.

To all whom it may concern:

Be it known that I, CHARLES E. McADOW, a citizen of the United States, residing at Jersey City, in the county of Hudson and State of New Jersey, have invented a new, original, and ornamental Design for a Casing for Combined Vending and Weighing Machines, of which the following is a specification, reference being had to the accompanying drawing, forming part thereof.

The figure is a perspective view of a casing for combined vending and weighing machines, showing my new design.

I claim:

The ornamental design for casing for combined vending and weighing machines, as shown.

CHARLES E. McADOW.
